AUTOMATIC GAS APPLIANCE

Frank A. Gauger, Milwaukee, Wis.

Application August 14, 1933, Serial No. 684,949

11 Claims. (Cl. 236—21)

This invention relates to an automatic gas appliance, and is particularly directed to an automatic storage hot water heater.

In storage heaters, as heretofore constructed, there were a number of losses. For instance, after the heater had operated and had cut off there was a continual circulation of air through the heater which cooled the heater and wasted the heat stored in the metal parts of the heater. This was true, whether the heater was a separate unit outside of the storage tank, and even more so when the heater was built into the storage tank as the air circulation cooled the heater parts and also cooled the contents of the storage tank as the circulation of cooling air, in this latter case, was through the storage tank.

Another loss was due to the constant waste from the pilot light. This loss is really material for it continues for a full twenty-four hours each day and, as compared with the time during which the heater is active, is a very long relative period.

This invention is designed to overcome the defects noted above, and objects of this invention are to provide on the one hand storage or other type of heater which automatically closes off the passages for the products of combustion after the heater has ceased to function and thus prevents a cooling circulation of air, and on the other hand extinguishes the pilot light during the periods of inaction, again automatically lighting the pilot light when the heater is again called into operation.

Further objects are to provide a very simple device for accomplishing these desirable results, and one that may be cheaply manufactured and readily installed.

Further and more specific objects are to provide a double safety feature for the automatic lighting of the device, so that even if a relatively slow thermally responsive device controlled the main valve, that even if the pilot light of such device had been extinguished and the device had not yet responded or settled back to its inoperative position, nevertheless an auxiliary pilot light is maintained until the thermally responsive device has regained its original state.

Since the circulatory passages for the heater are closed after the heater ceases burning, it is clear that if the main burner were again turned on, with the passages closed, there would be great danger of an explosion. This invention, therefore, has for its further object the provision of absolutely reliable means for opening the circulatory passageways under all conditions when-

ever the main burner is turned on, such means being so constructed that it is impossible to turn on the main burner without opening the passageways.

An embodiment of the invention is shown in the accompanying drawing, in which:

Figure 1 is a view, somewhat diagrammatic and broken away, of a storage heater.

Figure 2 is an enlarged sectional view on the line 2—2 of Figure 1.

Referring to the drawing, it will be seen that a storage tank has been shown as provided with a heater built into and forming a unitary structure with the tank. The drawing shows the tank broken away, but obviously it may be as tall or as large as desired.

The tank 1 has a dome-shaped shell 2 forming the bottom wall of the water compartment, and has a bottom wall 3, and is carried in any suitable manner as by means of legs 4, for instance. A combustion space is thus provided between the walls 2 and 3, and an inlet pipe 5 opens into the space and leads fresh air into the combustion chamber. A flue 6 leads upwardly from such chamber and has an outlet pipe 7 passing outwardly through the tank.

The tank is heavily insulated as indicated at 8 and this insulation may be surrounded by an outer protecting metal shell 9, if desired. A cold water inlet pipe 10 leads into the lower portion of the tank and a hot water outlet pipe 11 leads from the tank. Obviously the outlet pipe is preferably insulated (not shown) in the usual manner.

A lower shutter 12 and an upper shutter 13 close the air inlet pipe 5 and the outlet pipe 7 when the burner is not in operation. These shutters may be of similar construction and pass into slots cut half way through the pipes as indicated. Each shutter may be carried by a short shaft 14 provided with a crank 15, such cranks being joined by a light connecting rod 16. One of the shutters is shown in raised position in Figure 2. It is preferable to form the pipes and shutters oval as indicated in Figure 2. It is to be understood that other means may be used in place of that specifically shown.

The main burner 17 is located within the combustion chamber, the main pilot 18 projects into such chamber, and it is to be particularly noted that an auxiliary or safety pilot 19 is located adjacent both the main pilot and the burner 17. The main burner is controlled by an electromagnetic valve 20 and the main pilot 18 is controlled by a smaller electromagnetic valve 21.

The auxiliary pilot is controlled by a valve 22,

operated by a rod 23 in a manner hereinafter to appear. It is to be noted that both pilots are supplied through a by-pass pipe 23' independently of the main valve 20 and that the auxiliary pilot 19 is independent of the valve 21 of the main pilot 18.

A bi-metallic thermostatic member 24 is carried by the main pilot and moves downwardly when the main pilot is lighted. A light, pivoted lever 25, has its free end bearing against the underside of the member 24 and has its other end connected to the rod 23 so that when the thermostatic member is heated by the main pilot, the rod 23 moves upwardly and opens the valve 22 of the auxiliary pilot 19.

A mercury switch 26 is pivotally carried in a small housing 27 through which the rod 23 freely passes, and is tilted to closed position by the upward movement of the rod, and is tilted to open position by a downward movement of the rod.

An ignition electrode 28 is provided for the main pilot 18 and is supplied from the ignition transformer 29. It is preferable to provide a switch operated from the main valve 20 for opening the circuit of the primary of the ignition transformer when the main valve opens. This may be done in any suitable manner. For instance, the movable contact 30 of such switch may be carried by an insulating rod 31 operated by the plunger 32 of the electromagnetic main valve 20. This movable contact may normally bridge stationary contacts connected by means of conductors 33 and 34 in the circuit of the primary of the ignition transformer 29.

A thermostatic switch 35 is carried by the tank and has the portion 36 (which houses the temperature responsive elements) projecting into the tank. Preferably this thermostatic switch is adjustable. It has not been shown in detail as it may be any standard type desired.

This thermostatic switch controls the connecting of all of the electrical apparatus to the supply lines or mains 37, which latter may be either the usual lighting mains, or may be low voltage mains supplied from a small step-down transformer, such as a bell ringing transformer. It is preferable to use low voltage to avoid the necessity of providing conduit.

The branch supply conductors 38 and 39 supply all of the electrical devices, namely, the electromagnetic valves 20 and 21, and the ignition transformer 29. They are all controlled from the main thermostatic switch 35 which is responsive to water temperatures.

It is to be noted, however, that the ignition transformer 29 is controlled jointly by the thermostatic switch 35 and the switch 30 of the main valve 20; that the electromagnetic valve 21 of the main pilot light 18 is controlled solely by the thermostatic switch 29; and that the electromagnetic main valve 20 is controlled jointly by the thermostatic switch 35 and the mercury switch 26, the latter being controlled by the thermostatic member 24 of the main pilot.

The operation of the apparatus is as follows:— If the hot water has reached the member 36, the thermostatic switch 35 holds all circuits open. If a replenishing of hot water is required, the thermostatic switch 35 closes and, as the switch 30 is closed, the ignition transformer is thrown into operation. Also, the electromagnetic valve 21 of the main pilot light 18 is opened and the main pilot light is, therefore, lighted.

When the thermostatic member 24 of the main

pilot is sufficiently heated by the main pilot, it moves downwardly, thus raising the rod 23 through the medium of the lever 25. This opens the valve 22 of the auxiliary pilot 19, which immediately lights, and also tilts and thereby closes the mercury switch 26. The mercury switch completes the circuit for the main electromagnetic valve 20 and this valve opens, thereby turning on the gas for the main burner 17.

It is to be noted, particularly, that when the main valve 20 opens, its plunger 32 rises and moves the rod 16 upwardly, thereby opening both the upper shutter 13 and the lower shutter 12. This allows fresh air to enter the combustion chamber through the pipe 5, and allows the products of combustion to be discharged through the pipe 7. Further, the switch 30 is opened by the electromagnetic main valve 20 and the ignition transformer ceases to function.

After the requisite amount of water has been heated, the thermostatic switch, or main thermostatic member 35, opens and all circuits are then held open. However, it is to be noted that the auxiliary pilot 19 remains lighted until the thermostatic member 24 of the main pilot has cooled. Therefore, if a sudden demand should be made for hot water before the thermostatic member 24 of the main pilot 18 had cooled sufficiently, no harm would be done as the auxiliary pilot would light the burner 17, even in the event of failure or delayed action of the main pilot 18.

This is an important precautionary measure, as it precludes any possibility of an explosion from delayed action or failure of the main pilot 18, even under the abnormal condition outlined above.

On the other hand, after the thermostatic member 24 of the main pilot 18 has cooled, gas cannot be turned on for the main burner until the main pilot has been lighted and has heated its thermostatic member 24.

When the device is not in operation, both pilots are out, it being noted that the auxiliary pilot is cut out when the thermostatic member 24 of the main pilot has cooled, and that the main pilot is cut out when the main thermostatic switch 35 has opened. There is, thus, no waste from the pilot lights during the inactive period of the apparatus.

Further, there is no waste due to circulation of air through the heater during the inactive period of the device, as the circulatory passages are closed by the shutters.

It will be seen that a novel type of gas appliance has been disclosed, which may be employed for a storage water heater, or may be employed for other purposes if desired.

It will be seen further, that there is no undesirable cooling due to circulation of air when the device is not in operation, nor is there any waste from the pilot lights.

The device is very simple in construction and is thoroughly reliable in operation. It may be cheaply built and readily installed.

Although this invention has been described in considerable detail, it is to be understood that such description is intended as illustrative rather than limiting, as the invention may be variously embodied and is to be interpreted as claimed.

I claim:

1. An automatic gas appliance comprising a main burner, a main pilot light, an auxiliary pilot light, an automatic valve controlling said main pilot light, ignition means for said main pilot light, a thermostatically controlled auxiliary

valve controlled by said main pilot light and controlling said auxiliary pilot light, and an automatic valve for said main burner controlled simultaneously with said auxiliary valve.

- 5 2. A gas appliance comprising a main burner, an electromagnetic valve therefor, a main pilot light, an electromagnetic valve for said main pilot light, a thermostatic device responsive to said main pilot light, an electric switch controlled by said thermostatic device, an auxiliary pilot light, a valve controlled from said thermostatic device for controlling said auxiliary pilot light, ignition means for said main pilot light, and a main thermostatic means controlling said ignition means and both said electromagnetic valves, said switch additionally controlling the electromagnetic valve of said main burner.

10 3. A gas appliance comprising a main burner, an electromagnetic valve therefor, a main pilot light, an electromagnetic valve for said main pilot light, a thermostatic device responsive to said main pilot light, an electric switch controlled by said thermostatic device, an auxiliary pilot light, a valve controlled from said thermostatic device for controlling said auxiliary pilot light, ignition means for said main pilot light, and a main thermostatic means controlling said ignition means and both said electromagnetic valves, said switch additionally controlling the electromagnetic valve of said main burner.

15 4. In a gas appliance, the combination of a main burner, a first pilot light provided with thermostatic means, ignition means for said first pilot light, a second pilot light, and a valve for said main burner, said thermostatic means controlling said second pilot light and the valve for said main burner, said second pilot light remaining lighted until said thermostatic means returns to its cooled position.

20 5. In a gas appliance, a liquid receiving tank, a main burner for heating the contents of said tank and having a combustion chamber within which such burner is located, thermostatic means responsive to the temperature of said liquid, a pilot light having thermostatic means adapted to be heated by said pilot light, ignition means for said pilot light, an auxiliary pilot light controlled from the thermostatic means of said first mentioned pilot light, means controlled by the thermostatic means of said first mentioned pilot light for controlling said main burner, and a pair of shutters for controlling the circulation of air through said combustion chamber, said shutters being controlled by said last mentioned means, said pilot lights, said main burner, and said shutters being controlled from said first mentioned thermostatic means.

25 6. In a gas appliance, the combination of a liquid receiving tank, means for heating the contents of said tank comprising a combustion chamber, a main burner within said chamber, said chamber having inlet and outlet openings, thermostatic means responsive to the temperature of the liquid within said tank, a pilot light having thermostatic means adapted to be heated thereby, ignition means for said pilot light, an auxiliary pilot light controlled from the thermostatic means of said first mentioned pilot light, an electromagnetic valve for controlling said main burner, a switch controlling said electromagnetic valve and operated from the thermostatic means of the first mentioned pilot light, and a pair of shutters in the inlet and outlet of said combustion

chamber, said shutters being directly opened and closed by the electromagnetic valve of said main burner.

7. In a gas appliance, the combination of a liquid receiving tank, means for heating the contents of said tank comprising a combustion chamber, a main burner within said chamber, said chamber having inlet and outlet openings, thermostatic means responsive to the temperature of the liquid within said tank, a pilot light having thermostatic means adapted to be heated thereby, ignition means for said pilot light, an auxiliary pilot light controlled from the thermostatic means of said first mentioned pilot light, an electromagnetic valve for controlling said main burner, a switch controlling said electromagnetic valve and operated from the thermostatic means of the first mentioned pilot light, a pair of shutters in the inlet and outlet of said combustion chamber, said shutters being directly opened and closed by the electromagnetic valve of said main burner, and means operated by the electromagnetic means of said main burner for cutting off said ignition means when said electromagnetic valve opens.

8. In a gas appliance, the combination of a liquid receiving tank, means for heating the contents of said tank comprising a combustion chamber, a main burner within said chamber, said chamber having inlet and outlet openings, 30 thermostatic means responsive to the temperature of the liquid within said tank, a pilot light having thermostatic means adapted to be heated thereby, ignition means for said pilot light, an auxiliary pilot light controlled from the thermostatic means of said first mentioned pilot light, 35 an electromagnetic valve for controlling said main burner, a switch controlling said electromagnetic valve and operated from the thermostatic means of the first mentioned pilot light, 40 a pair of shutters in the inlet and outlet of said combustion chamber, said shutters being directly opened and closed by the electromagnetic valve of said main burner, and means operated by the electromagnetic means of said main burner for 45 putting off said ignition means when said electromagnetic valve opens, said auxiliary pilot remaining lighted until the thermostatic means of the first mentioned pilot has returned to its cooled position.

9. In a gas appliance, the combination of a main burner, an electromagnetic valve therefor, a master circuit controller, a main pilot light controlled from said master controller, electric ignition means controlled from both said master controller and from said electromagnetic valve for said main burner, an auxiliary pilot light, thermostatic means actuated from said main pilot light for controlling said auxiliary pilot light, said electromagnetic valve for said main burner being jointly controlled by said main controller and said thermostatic means, and electric circuits for said main circuit controller, said electromagnetic valve, and said ignition device. 50 55 60

10. In a gas appliance, the combination of a main burner, an electromagnetic valve therefor, a master circuit controller, a main pilot light controlled from said master controller, electric ignition means controlled from both said master controller and from said electromagnetic valve for said main burner, an auxiliary pilot light, thermostatic means actuated from said main pilot light for controlling said auxiliary pilot light, said electromagnetic valve for said main burner being jointly controlled by said main

controller and said thermostatic means, and electric circuits for said main circuit controller, said electromagnetic valve, and said ignition device, said main circuit controller being a master control for all electric circuits.

5 11. In a gas appliance, the combination of a main burner, an electromagnetic valve therefor, a master circuit controller, a main pilot light, controlled from said master controller, electric 10 ignition means controlled from both said master controller and from said electromagnetic valve for said main burner, an auxiliary pilot light, thermostatic means actuated from said main

pilot light for controlling said auxiliary pilot light, said electromagnetic valve for said main burner being jointly controlled by said main controller and said thermostatic means, and electric circuits for said main circuit controller, said electromagnetic valve, and said ignition device, said auxiliary pilot light being lighted from said main pilot light, said thermostatic means maintaining the auxiliary pilot light after ignition for a material length of time irrespective of the condition 10 of any of the electric circuits.
